Atty.

UNITED STATES PATENT OFFICE

WILHELM LUDOWICI, OF JOCKGRIM, PFALZ, GERMANY

SELF-DISCHARGING WAGON

Application filed March 3, 1932, Serial No. 596,468, and in Germany October 7, 1930.

My invention relates to self-discharging wagons. It is an object of my invention to provide a wagon of the kind described which is particularly suitable for handling materials of a more or less sticky character.

To this end, in combination with a frame and a bottom plate mounted to rock on the frame, I provide a car body which is placed on the bottom plate in inverted position, being open at the top and at the bottom. The car body is mounted to be tilted on the frame about an axis at its top through the medium of the bottom plate.

Self-discharging wagons as designed heretofore present the drawback that while there is no trouble about handling dry and readily flowing materials it is very difficult to handle sticky materials or materials which have a tendency to settle into more or less compact conglomerates under the action of the inevitable shocks they undergo during shipping, and to stick to the car body and the bottom plate. With such materials it is often necessary to employ labor for detaching the material and cleaning the car body.

Another drawback of self-discharging wagons as designed heretofore is the unsatisfactory protection against inertia forces. The mechanism for discharging the wagon is subjected to high stress by these forces and the moving members are not balanced to a sufficient extent so that their reaction on the frame of the car is very detrimental, particularly if the mechanism is operated at high velocity.

It is another object of my invention to eliminate this drawback. To this end I so arrange the tilting car body and its rocking bottom plate that the load on the bottom plate balances the weight of the car body.

In a preferred embodiment of my invention I provide a car body which is wider at the bottom than at the top, and means for discharging to opposite sides of the track by selectively tipping the car body about one of two axes at opposite sides of its top.

In the drawing affixed to this specification and forming part thereof a double-sided self-discharging wagon is illustrated diagrammatically by way of example.

In the drawing

Fig. 1 is an elevation, partly in section on the central vertical plane of the wagon,

Fig. 2 is an end elevation, viewed from the left in Fig. 1, with the car body and bottom plate in normal position,

Fig. 3 is an end elevation viewed like Fig. 2 but showing the body and the bottom plate in discharging position,

Fig. 4 is a section on the line IV-IV in Fig. 1, and

Fig. 5 shows one end of a modified wagon, partly in section on its central vertical plane.

Referring now to the drawing, 1 is the frame of the wagon which may be designed in any suitable manner, and 2, 3 are two four-wheeled trucks on which the frame is supported. 4 and 5 are vertical end frames at opposite ends of the wagon, 6 are bracing members extending from the ends of the frame 1 to the tops of the adjacent end frames 4 and 5, and 7, 8 are open bearings on the upper transom of each end frame.

Mounted to rotate in the bearings 7, 7 and 8, 8 are journals at the ends of two parallel shafts 9 and 10 which may extend along the sides of the top of the car body 11. By way of example the car body is shown as a truncated pyramid which is preferable to a square box as the sloping walls favor the separation of the body and the material. 12 are slide bars, preferably of channel section, which are secured to the ends of the car body 11 by suitable brackets, 13 are blocks which are mounted to slide in the bars, 14 are piston rods, each with a piston 16 at its lower end while its upper end is pivoted to the corresponding slide 13, 15 are cylinders in which the pistons 16 are mounted to slide, and 17 are trunnions on transverse bars 18 in the two end frames 4 and 5 about which the cylinders 15 are mounted to rock. The cylinders may contain a charge of air or gas or may be designed to draw in atmospheric air and to compress it, in order to damp the movements of the mechanism. The cylinders may also be supplied with gas or liquid under pressure for tilting the car body. In this case means for manual operation may be dispensed with, or the pneumatic or hydrau-

100

lic and the manual means may be provided together for alternating operation.

The shafts 9 and 10 serve alternately as the axis about which the car body 11 is tilted. Fig. 3 shows the car body 11 and the bottom plate 30 opened out toward the left. The car body is tilted about the bearings which are opposite the discharging side, in the present instance, the bearings 8, 8 for the journals of the shaft 10. The journals of that shaft 9 or 10 about which the car body 11 is tilted, are retained by links 19 which are mounted to rock and to slide on pivots 20 at the outer faces of the end frames 4 and 5. The links 19 are normally at the outer ends of their pivots and beyond reach of the journals, as shown for the link at the left in Fig. 3. Each link has a hole 21 at its free end which is adapted to fit on the journal of the corresponding shaft when the shaft is in its bearing and the links are moved inwardly as shown in Figs. 1, 2 and 5. In Fig. 2 the links 19 at both sides engage the corresponding journals. When it is desired to tilt the car body, as shown in Fig. 3, the links 19 for the shaft about which the car body is tilted, in the present instance, the shaft 10, are left in their journal-engaging position while the links for the other shaft, in the present instance, 9, are shifted to the ends of their pivots so as to relieve the journals, and hang down from their pivots 20 as shown in Fig. 3.

22 are central bearings on the frame 1, 23 is a central longitudinal shaft in the bearings, and 24, 24 are plain rollers or wheels for channeled rails 25 at the lower face of the bottom plate 30 to run on. 26 and 27 are pinions near the ends of the shaft and 28, 29 are racks on the lower face of the bottom plate 30 meshing with the respective pinions. 31 and 32 are a pair of links, Fig. 4, each of which extends from one side of the bottom plate 30 to the opposite side of the car body 11, and 33, 34 are rows of rollers at opposite sides of the bottom of the car body 11 which connect the car body to the bottom plate.

A worm wheel 35 is secured to one end of the central shaft 23 as shown in Fig. 2 and its worm 36 is mounted on a transverse shaft 37 in bearings 38 on the end frame 4. Any suitable means, not shown, may be provided for rotating the shaft 37. Obviously the wheels 35, the worm 36 and the shaft 37 may be duplicated at the other end frame 5.

Fig. 5 shows one end of the wagon equipped for exclusively hydraulic or pneumatic operation, with the worm gear for the shaft 23 omitted. As mentioned, pneumatic or hydraulic means and means for manual operation may be provided together and operated alternately.

If the shaft 37 is rotated the pinions 26 and 27 move the bottom plate 30 toward the discharging side. At the same time the

side of the bottom plate which is opposite the discharging side, is retained by the rollers 33 or 34 at the lower end of the car body which bear on the bottom plate so that in addition to being displaced transversely the bottom plate performs a rocking movement about the pinions 26, 27. The transverse and rocking movements of the bottom plate 30 are transmitted to the car body 11 by the links 31 and 32 which cause the car body to be tilted about the shaft 10. The rollers 33 as that side of the car body which opens out, are lifted off the bottom plate 30 while the rollers 34 at the opposite side bear on the bottom plate, so that the bottom plate rocks, and the car body is tilted, in opposite directions. In this manner the car body and the bottom plate move with the axis of the shaft 10 as the fixed pivot of the system and open out while being shifted toward the discharging side at the same time. The material on the bottom plate 30 is completely exposed by the car body 11 and will not be interfered with by the body as it slides down from the gradually steepening slope presented by the bottom plate 30. It is obvious that in this manner even sticky and otherwise obstructive materials may be discharged without trouble. The discharging is favored if the car body is a truncated pyramid, i. e. wider at the bottom than at the top, as shown, because the material comes off the sloping walls of the car body more easily than in a body having parallel walls.

The inertia forces assist the discharging operation in a very favorable manner. The car body 11 moves opposite direction to the bottom plate 30 and the material which slides down on the bottom plate, the car body being lifted while the free side of the bottom plate is lowered. This compares favorably with the defective balancing of inertia forces in the wagons as designed heretofore. It is a particular advantage of my arrangement that the balancing of the inertia forces is effected without providing extra members or weights for this purpose. By means of the links 31 and 32 the bottom plate and the car body are gradually opened out while the bottom plate moves in rotating the rollers 34. Initially the mechanism may be considered as rotating about the shaft 10 so that the major portion of the moving weight, i. e., the material, is displaced horizontally in the discharging direction. This horizontal movement is gradually translated into downward movement by the increasing slope of the bottom plate 30. The bottom plate 30, as it is displaced by the pinions 26, 27, acts as a lever under the weight of the material and the weight of the car body is automatically raised by the weight of the material acting on the rollers 34 at this leverage, so that the force required for discharging is small. Toward the end of the discharging operation the ma-

terial begins to slide down on the bottom plate 30, relieving the bottom plate. The weight of the car body tends to return the parts into their initial position.

If it is desired to discharge to the left, the same operation is performed with the bearings 7 closed by their links 19 and the bearings 8 opened.

It will be understood that any suitable means other than the links 19 may be provided for opening and closing the bearings 7, 7 and 8, 8 and that these means may be operated by any suitable mechanism, not shown.

The links 31 and 32 which connect the bottom plate to the car body may be arranged outside the car body instead of within, as shown. If arranged outside the links are protected against any detrimental influences the material may exert on them.

If the wagon is designed for manual operation through the medium of the shaft, or shafts, 37, the pistons 16 will move to the upper ends of their cylinders 15 during the tilting and rocking movements described, the blocks 13 sliding in the channel bars 12 as shown in Fig. 3 and upon the subsequent return of the car body 11 and the bottom plate 30 in the normal position the pistons 16 return into their initial position, Fig. 2. The pistons move in their cylinders against the resistance of a gas or liquid which they compress or expel, and damp the movements of the several members.

In a wagon which is operated by gas or liquid in the cylinders 15 the manually operated means, if provided, are thrown out by interrupting the connection of the worm 36 and its wheel 35 so that the central shaft 23 rotates freely. The pinions 26 are not required if the car is operated exclusively by the cylinders 15, 15 but are preferably provided for guiding the bottom plate 30 at both ends so as to avoid edging of the plate if owing to any irregularity the piston in one of the cylinders lags or leads with respect to the other piston.

I wish it to be understood that I do not desire to be limited to the exact details of construction shown and described, for obvious modifications will occur to a person skilled in the art.

In the claims affixed to this specification no selection of any particular modification of the invention is intended to the exclusion of other modifications thereof and the right to subsequently make claim to any modification not covered by these claims is expressly reserved.

I claim:—

1. A self-discharging wagon comprising a frame, a bottom plate mounted to rock on and to be displaced transversely with respect to said frame, an inverted car body mounted to be tilted about an axis on said frame, and means for tilting said car body about said axis

and for rocking and transversely displacing said bottom plate.

2. A self-discharging wagon comprising a frame, a bottom plate mounted to rock on and to be displaced transversely with respect to said frame, an inverted car body mounted to be tilted about an axis on said frame, means for transversely displacing said bottom plate, and means operatively connecting said car body and said bottom plate for imparting rocking movement to said bottom plate while said car body is being tilted about said axis.

3. A self-discharging wagon comprising a frame, a bottom plate mounted to rock on and to be displaced transversely with respect to said frame, an inverted car body mounted to be tilted about an axis on said frame, means for tilting said car body about said axis, and means operatively connected to said car body for transversely displacing and rocking said bottom plate.

4. A self-discharging wagon comprising a frame, a bottom plate mounted to rock on and to be displaced transversely with respect to said frame, an inverted car body mounted to be tilted about an axis on said frame, means for tilting said car body about said axis and for rocking and transversely displacing said bottom plate, and means for damping the movements of said car body and said bottom plate.

5. A self-discharging wagon comprising a frame, a bottom plate mounted to rock on and to be displaced transversely with respect to said frame, an inverted car body mounted to be tilted about an axis on said frame, a central longitudinal shaft extending along said frame, means for rotating said shaft, means on said shaft for transversely displacing said bottom plate, and means operatively connecting said car body and said bottom plate for imparting rocking movement to said bottom plate while said car body is being tilted about said axis.

6. A self-discharging wagon comprising a frame, a bottom plate mounted to rock on and to be displaced transversely with respect to said frame, an inverted car body mounted to be tilted about an axis on said frame, means for transversely displacing said bottom plate, and a pair of links each extending from one side of said bottom plate to the opposite side of said car body.

7. A self-discharging wagon comprising a frame, a bottom plate mounted to rock on and to be displaced transversely with respect to said frame, an inverted car body having walls sloping outwardly from its top to its bottom mounted to be tilted about an axis on said frame, and means for tilting said car body about said axis and for rocking and transversely displacing said bottom plate.

8. A self-discharging wagon comprising a frame, a bottom plate mounted to rock on and to be displaced transversely with respect

to said frame, an inverted car body, shafts at both sides of the top of said car body, bearings for the reception of said shafts at opposite sides of said frame, means for opening and closing said bearings, and means for tilting said car body about the axis of the shaft the bearings of which are closed and for rocking and transversely displacing said bottom plate.

9. A self-discharging wagon comprising a frame, a bottom plate mounted to rock on and to be displaced transversely with respect to said frame, rollers on which said bottom plate is supported, an inverted car body mounted to be tilted about an axis on said frame, and means for tilting said car body about said axis and for rocking and transversely displacing said bottom plate.

10. A self-discharging wagon comprising a frame, a bottom plate mounted to rock on and to be displaced transversely with respect to said frame, an inverted car body, shafts at both sides of the top of said car body, bearings for the reception of said shafts at opposite sides of said frame, means for opening and closing said bearings, a central longitudinal shaft extending along said frame, a pinion on said shaft, a rack on said bottom plate meshing with said shaft, means for rotating said shaft, and means for tilting said car body about said axis through the medium of said bottom plate.

11. A self-discharging wagon comprising a frame, a bottom plate mounted to rock on and to be displaced transversely with respect to said frame, an inverted car body, shafts at both sides of the top of said car body, bearings for the reception of said shafts at opposite sides of said frame, means for opening and closing said bearings, a central longitudinal shaft extending along said frame, a pinion on said shaft, a rack on said bottom plate meshing with said shaft, manually operated means for rotating said shaft, and means for tilting said car body about said axis through the medium of said bottom plate.

In testimony whereof I affix my signature.
WILHELM LUDOWICI.
